DESIGN FOR A SHOE SOLE

Ray R. Reeves, Los Angeles, Calif.

Application January 9, 1940, Serial No. 89,356

Term of patent 14 years

To all whom it may concern:

Be it known that I, Ray R. Reeves, a citizen of the United States, residing at Los Angeles, in the county of Los Angeles and State of California, have invented a new, original, and ornamental Design for a Shoe Sole, of which the following is a specification, reference being had to the accompanying drawing, forming part thereof.

Figure 1 is a view in side elevation of the shoe

sole embodying my new design; Fig. 2 is a bottom plan view of the same; Fig. 3 is a longitudinal sectional view taken substantially upon the line 3—3 of Fig. 2 and looking in the direction of the arrows as indicated.

I claim:

The ornamental design for a shoe sole, as shown.

RAY R. REEVES.
